(57) **CLAIM**

The ornamental design for a spittoon flask, as shown and described.

DESCRIPTION

FIG. 1 is a perspective view of the spittoon flask showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an exploded perspective view, showing the funnel, thereof.

The broken lines shown in the figures are for the purpose of illustrating portions of the spittoon flask and form no part of the claimed design.
